UNITED STATES PATENT OFFICE

ALFRED F. MCCOLLUM, OF BLOOMSBURG, PENNSYLVANIA, ASSIGNOR TO THE MAGEE CARPET CO., OF BLOOMSBURG, PENNSYLVANIA, A CORPORATION OF PENNSYLVANIA

MECHANICAL MEANS FOR SEVERING OR TRIMMING THE EDGES OF CARPETS

Application filed March 23, 1926. Serial No. 96,897.

The object of this invention is to provide improved mechanical means for severing or trimming the edges of carpets prior to the binding of said edges or to the attachment thereto of a suitable fringe or ornamental border.

Another and more specific object of the invention is to provide means for movably supporting the carpet during the cutting operation so that the latter may with facility be moved past the relatively stationary cutting means.

In the attached drawings:

Figure 1 is a more or less diagrammatic front elevation of a machine made in accordance with my invention;

Fig. 2 is a section on the line 2—2, Fig. 1, and

Fig. 3 is an enlarged view in perspective of the essential parts of the cutting mechanism.

In practicing my invention, I have found it possible to utilize a standard sewing machine, the details of whose mechanism requires no description here, except as to those parts directly affected by the present invention.

With reference therefore to Fig. 3, I have shown in their proper relative positions the presser bar 1 of a sewing machine of well known make, which carries at its lower end a presser foot 2 adapted to cooperate with an underlying feeding foot 3 in well known manner to effect an intermittent movement of the material through the machine. For accomplishing this movement, the presser foot is mounted in the present instance upon a bar 4 which at its forward end is supported upon a relatively fixed roller 5 and at its rear end is pivotally secured to the upper end of an oscillatory bar 6 whereby the bar 4 is given a longitudinal reciprocatory movement required by the feeding foot for its operation. The under portion of that part 45 of the bar resting on the roller 5 is cam-shaped so that at the forward end of the stroke the presser foot is carried toward the under side of the feeding foot, whereby the latter grips the under side of that portion 50 of the carpet which may be inserted between

the presser foot and the feeding foot, while at the rear end of the stroke, the feeding foot is dropped further from the presser foot to release the carpet until the feeding foot again engages at the forward end of the stroke. During a portion of the rearward movement of the feeding foot, the latter engages the carpet as described and carries the latter backwardly with it. These are standard parts of a sewing machine mechanism and form only an incidental part of the present invention.

Again referring to Fig. 3, the reference numeral 7 indicates the needle bar which in the present instance, instead of carrying a needle, has secured to its lower end a cutting blade 8 whose cutting edge is directed towards the front of the machine or towards that side from which the carpet is fed between the presser foot and the feeding foot. This blade is tapered towards its lower end and extends between the bifurcated ends of the presser foot and through the longitudinal slot of the feeding foot.

In the operation of the machine, the edge of the carpet which is to be severed is passed between the presser foot 2 and the feeding foot 3 in the usual manner of sewing and is advanced with an intermittent movement toward the rear of the machine. At the same time, the needle bar 7 is reciprocated vertically so that the blade 8 is rapidly reciprocated in a vertical direction.

It will be understood that the reciprocation of the feeding foot is an intermittent one and is synchronized with the reciprocation of the needle bar 7 so that during the down or cutting stroke of the needle bar, the bar 4 remains stationary in an advance position in which as previously described the feeding foot bears against and confines the edge of the carpet between itself and the presser foot. It will also be noted that the cutting edge of the blade 8 curves outwardly toward the top away from the bar 7 and toward the front of the machine so that the actual division made in the fabric at each downward stroke of the blade extends well in advance or forwardly of the cutting edge of the knife when the latter is elevated, as shown in Fig. 3. In

the sequence of operations and following the downward movement of the blade 8 and during the return upward movement of the blade, the feeding foot is moved rearwardly carrying with it the carpet so that as the blade again descends, it again comes into contact with an unsevered part of the fabric. The functions of the various parts and the sequence of operation, with the exception of the actual cutting, are the same as the sequence of operations in the standard sewing machine and will be readily understood.

In order to support the carpet and to facilitate the passage of the edge portion through the cutting mechanism, I preferably provide a table or conveyor consisting of a plurality of rotatable rolls 9 arranged on parallel axes substantially at right angles to the path of movement of the carpet through the machine. These rolls also are preferably arranged on an inclined plane, the lower end of which is toward the rear of the machine so that the rug tends to pass down the table by gravity, thereby assisting the movement of the carpet through the cutting mechanism.

In Fig. 1, I have indicated a carpet in position upon the rolls 9, the carpet designated by the reference numeral 11 being rolled with its edge extending under the cutting mechanism.

I claim:

1. In a fabric-cutting machine, the combination with a work support, of a vertically reciprocating cutting blade having an inclined cutting edge, mechanism for actuating said blade, mechanism operating in synchronism with the blade for intermittently advancing the fabric with respect to the blade, said advancing mechanism including a fabric-actuating member adapted to engage the under side of the fabric at points adjacent said blade whereby said member functions also to support the fabric at points immediately adjacent the cutting operation, and means adapted to engage the top of said fabric and cooperative with said underlying member to anchor the fabric during the cutting operation.
2. In a fabric-cutting machine, the combination with a vertically reciprocating blade having an inclined cutting edge, of cooperating elements adapted respectively to engage the top and bottom of the fabric at points immediately adjacent the said blade for anchoring the fabric during the cutting operation, and mechanism including one of said elements for intermittently advancing the fabric with respect to and in timed relation with the movements of said blade.

ALFRED F. McCOLLUM.
